METAL ROOFING

Karl Roth, Terre Haute, Ind.

Application July 16, 1937, Serial No. 153,955

1 Claim. (Cl. 108—18)

This invention relates to metal roofing and has for a primary object the provision of a metal sheet unit which may be used in multiple in laying roofs, the main feature being that each unit may be originally coated in a flat sheet and then rolled or otherwise formed into such shape that there will be no sharp bends but only smooth, rounded corners, whereby the coating may remain firmly attached to the sheet without danger of its peeling at the bends or curves as has been heretofore encountered in roofing units of the nature herein employed.

A still further important advantage of the invention is that the individual units may be secured to the roof sheathing by nails driven through a corrugation of major height and additional nails may be driven through intermediate corrugations of minor height so as to bring the individual units down into firm contact with the sheathing where irregularities of the sheathing may exist.

A still further important feature of the invention is that the major corrugations may have the side walls closely approach the perpendicular so as to resist distortion when the securing nails are driven therethrough.

A still further important feature of the invention is found in the particular joint between the adjacent units which effectively prevents water leakage and at the same time avoids any sharp bends in the marginal edges of the sheets.

These and many other important features and advantages of the invention will be apparent to those versed in the art in the following description of the invention as illustrated in one particular form in the accompanying drawing, in which:

Fig. 1 is a top plan view of a fragment of roof embodying the invention.

Fig. 2, a transverse vertical section on line 2—2; and

Fig. 3, a detail in vertical transverse section through a modified form of lap between the sheets.

Like characters of reference indicate like parts throughout the several views in the drawing.

The metal sheet, generally designated by the numeral 10, is initially provided with some protective coat, such as zinc, while still in the flat sheet. The coated sheet is then pressed or preferably rolled to provide a plurality of spaced apart major ridges 11, herein shown as three in number. Between these major ridges 11 are a plurality of minor ridges 12 with intervening

grooves 13, providing the sheet with major and minor corrugations.

Referring to Fig. 2, sheet 10 when laid in the position indicated, has on its right hand side a tail piece 14, extending outwardly from the lower end of the outer ridge 11 in the plane including the under sides of the grooves 13. The flat tail portion 14 continues from under the first groove 13, across under the first minor ridge 12 and then curves upwardly and around under the second minor ridge 12 in a compressive contact thereunder to terminate in a line at least slightly beyond the center of the second minor ridge 12. Also it is to be noted that the first ridge 11, on the left hand side of the sheet 10 in this case, has its outer lower longitudinal edge 15 spaced a distance above the bottom of the groove 13 sufficiently to prevent water coming down the roof from passing thereunder. That is, the edge 15 is spaced above any likely depth of water that may appear on the roof. This left hand ridge 11 laps over the right hand major ridge 11' and has the first two grooves 13 resting by their undersides on the tail portion 14 of the next adjacent sheet. What moisture may creep upwardly past edge 15, under the overlapping ridge 11 and over the underlapping ridge 11' is caught over the tongue 14 as it approaches the minor ridge 12 in an air space there provided to break up the capillary action. This trapped moisture may then flow downwardly over the tongue portion 14 without travelling further transversely since the right hand end of the tongue 14 curls up and under and is in contact with the under side of the second minor ridge 12.

As indicated in Fig. 3, the major ridges 11 are of considerable elevation, in fact, are made to be higher than the ridges heretofore commonly employed in a corresponding sheet. The main feature in these major ridges 11 is that their side walls are carried upwardly to approach the perpendicular plane, whereby these ridges will not become distorted when the securing nails 16 are driven downwardly therethrough in the sheathing 17 thereunder. These nails 16 are preferably provided with lead washers 18 under their heads as is the usual practice to prevent leakage around the nails. It is to be noted that by providing these major ridges 11, through which the nails enter, combined with the minor corrugations, there are no sharp bends at the base of the major ridges as has heretofore been the case, and yet sufficient rigidity is secured to permit driving the nails 16. Furthermore, by providing the minor corrugations between the major

ridges there is sufficient elasticity to provide pushing toward the side walls of the major ridges in opposition to downward and spreading action by the pressure occasioned by driving the nails 5 16 as will cause permanent pressure against the lead washer 18, to maintain a permanent water seal without lifting the nails and at the same time permit expansion and contraction of the sheets under various weather conditions. Again 10 as above indicated, such as when there may be irregularities in the spacing and elevation of the sheathing boards 17, nails may be driven through the minor ridges 12 as desired, all without occasioning leakage through the sheet, since these 15 minor ridges 12 have their upper portions above the usual level that may be reached.

As indicated in Fig. 2, the tail portion extending from the right hand ridge 11, may be shortened from the tail 14 as indicated in Fig. 2, to have the 20 tail portion 19 in Fig. 3 extend in a flat manner from under the first groove 13 across the first minor ridge 12 and then turn upwardly into intimate contact with the outer downwardly sloping portion of the ridge 12, whereby an air space 20 25 is provided to break up capillary action between the overlapping sheet portion. This modified form as shown in Fig. 3 may be utilized where the sheet 10 is of a narrower width than that employed in Fig. 2.

30 It is therefore apparent that in the unique structure above described, a great many advantages are to be had over and above the type of metal roof sheets heretofore employed. There are no sharp bends, grooves, nor ridges in my 35 structure so that there is no occasion for the coating to start peeling at any place as a result of the forming of the sheet. Corrugations are formed of sufficient radius to prevent separating of the coating from the sheet. Not only are the above 40 indicated mechanical features obtained in my invention, but there is a highly desirably aesthetic appearance obtained by reason of the existence of the minor corrugations between the major ridges. An additional feature that may be noted in the 45 sheets formed in accordance with this invention, is that they may be nested and shipped readily without damaging the longitudinal edges as is

apparent in heretofore experience with sheets formed with V-like longitudinal edges.

While I have herein described my invention in the form as is now known to me, it is obvious that structural changes may be employed without departing from the spirit of the invention and I therefore do not desire to be limited to that precise form beyond the limitations of the following claim.

I claim:

10 A coated metal roofing sheet comprising a plurality of spaced apart upwardly extending major ridges, a plurality of corrugations intervening between said ridges, the under sides of the grooves of the intervening corrugations being in a common plane and the upper sides of the ridges of the intervening corrugations being in a common plane, the upper sides of said major ridges being in a plane removed above the upper plane of said corrugation ridges, said major ridges being curved 20 upwardly from a groove of said corrugations to have a side wall sloping but slightly outwardly from the perpendicular and having a top curving over and around therefrom into a downturned side wall of the same rate of but oppositely directed slope as that of the first wall, all of the said grooves and ridges including those in said corrugations and said major ridges being of sufficient curvature when formed as will retain said coating thereover in intimate contact without rupture, 30 one of said major ridges being along one side of the sheet and having its outer downturned wall terminating by a longitudinal edge at an elevation at least as high as the tops of the ridges of said corrugations, and another of said major 35 ridges being adjacent to the opposite sheet edge to have the outer wall of that ridge curved around into a laterally extending tongue in a plane common to that of the undersides of said corrugations, and an outer upturned end on said tongue, 40 said tongue end being positioned under the second of the minor ridges of said corrugations, said tongue end being curved around under and in intimate contact with the underside of that second minor ridge.
